UNITED STATES PATENT OFFICE

2,486,245

DEVICE FOR DISPENSING
LUBRICATING OIL

Fred G. Bates, Detroit, Mich.

Application December 8, 1944, Serial No. 567,261

2 Claims. (Cl. 222—83.5)

1

This invention relates to improvements in dispensers, and refers particularly to dispensers for supporting and opening oil cans for their contents to be emptied into the crank case of an automobile.

At the present time there are a number of dispensers on the market for this purpose which are provided with means for opening a can, but in most cases they merely tear one end of the can with the result that dishonest merchants sometimes insert fresh ends after refilling the cans with an inferior oil as the original label has not been defaced. Again most dispensers now on the market bend the partly severed portion of the can end inwardly with the result that this intact portion interferes with complete drainage so that the purchaser does not receive his full measure of oil. Again in many cases the dispensers are so constructed that it is easier and therefore customary to tear the can end prior to the insertion of the dispenser in the filler opening with the result that oil is often spilled upon the motor or other portions of the vehicle while the dispenser is being placed in the said opening.

It is an object of the invention to provide a dispenser formed at its lower extremity to fit into an oil inlet of a crank case, having means intermediately of its height for supporting a can therein, and a pivoted blade by movement of which both the side and one end of the can, and the seam connecting the end to the side, are severed, thereby making it unprofitable to attempt to refill the can and make it again oil tight; moreover the blade is so arranged that it also defaces the label upon the can.

Another object of the invention is to provide a dispenser wherein the blade is arranged to flex the partly severed portion of the can end downwardly and outwardly to facilitate the complete emptying of the can.

A further object of the invention is to provide such a dispenser including a closure adjacent its lower extremity which is opened and closed as the blade is moved. Thus I am to provide means for preventing oil from dripping onto the motor or other parts of the vehicle during removal of the dispenser since spring means are provided for returning the blade to its inoperative position and for moving the closure to shut position.

Yet another object of the invention is to provide a dispenser for insertion in the oil filler pipe of a crank case so constructed and arranged that an unopened can may be placed therein

2

and then opened so that spillage of oil cannot occur while the can is being placed in the dispenser.

Having thus stated some of the objects and advantages of the invention I will now describe it with the aid of the accompanying drawing in which:

Figure 1 illustrates a side elevation of the invention.

10 Figure 2 is a section on the line 2—2 of Figure 1.

Figures 3 and 4 are sections on the lines 3—3 and 4—4 respectively of Figure 2.

15 Figure 5 is a partial sectional view showing the blade in cutting position.

Figures 6 and 7 are sections on the lines 6—6 and 1—7 respectively of Figure 3, and

Figure 8 is a view showing a portion of can when cut by the blade.

20 Referring to the drawing, 1 designates a tubular container which is of reduced diameter toward its lower extremity. Extending inwardly from the wall of the container 1 intermediately of its height is a striker plate 2 having a vertical face 2a which is substantially radially disposed, and provided also on the inner face of the container 1 are one or more supports 3 the upper sides of which are in horizontal alignment with the top of the striker plate 2. These supports 15 3 and the top of the plate 2 form rests to support the underside of a can A.

25 Formed through the wall of the container 1 for a short distance above and below the top of the striker plate 2 is a vertical slot 4. Mounted on the outer face of the container as by suitable flanges 5 and a supporting member 5a is a narrow housing 6 into which the slot 4 opens. Extending through opposite sides of the housing 6 and disposed at right angles to an imaginary line drawn from the axis of the container is a hinge pin 7 on which a blade 8 is pivotally mounted. The blade is provided with one flat side to move contiguous to the vertical face 2a of the striker plate, and its outer edge is rearwardly tapered 30 from its striker plate contacting side.

35 Vertically slidable in the housing 6 is a block 9 having arms 10 which are pivotally attached to the blade 8 by a connecting pin 11 so that upon downward movement of the block 9 the blade 40 is turned from its position shown in Figure 3 to that shown in Figure 5 about the pin 7. This downward movement is imparted to the block 9 through a camming lever 12 rotatably supported in the housing and projecting outwardly therefrom. Secured to the blade 8 is a helical spring 45

14 the free end of which is in engagement with a stop 15 extending between and supported by opposite sides of the housing 8, so that as the blade is swung downwardly and inwardly the spring is placed under tension and therefore tends to return the said blade to its position shown in Figure 3. Projecting from the blade 8 and secured to one face thereof is an arm 16 the outer extremity of which is pivotally connected to a rod 17 which extends downwardly in the container 1 so that rotation of the blade about the pin 7 raises or lowers the said rod. Mounted in the container 1 adjacent its annular underside is an outlet member 18 having an opening 19 formed therethrough, and normally held against the underside of the latter and mounted on the lower end of the rod 17 is a closure member 20. Thus when the blade 8 is in its position shown in Figure 3 the closure member 20 is held against the underside of the opening 19 to form a seal and prevent the passage of oil therethrough, and when the blade is moved into its position shown in Figure 5 the closure member is lowered to its position indicated at 20a in Figure 3 and a free flow of oil through the opening 19 occurs.

Thus it will be clearly seen that upon movement of the blade 8 from its position shown in Figure 3 to that shown in Figure 5, the said blade first cuts the side of the can A, passes through the seam by which one end is secured to the said side and then also cuts the can end and forces a partially severed portion of the latter downward as shown at B in Figure 8.

While in the foregoing the preferred embodiment of the invention has been described and shown it is understood that alterations and modifications may be made thereto provided the said alterations and modifications fall within the scope of the appended claims.

What I claim is:

1. A dispenser including an annular container open at the top and bottom, said container being of uniform cross section from its upper extremity for a portion of its length to receive a can, the lower portion of the container being of decreasing cross sectional area toward its bottom extremity, said container being rigid throughout its

length whereby when its bottom extremity is inserted in a filler pipe the container is substantially vertically supported thereby, an annular seat in the container adjacent its lower extremity so that all oil flowing therefrom passes through the seat, a closure adapted to rest on said seat, spaced supporting means including a striker plate on the interior of the container toward its upper extremity to support the base of the can, a housing mounted on the outer face of the container, the latter being vertically slotted to provide an opening into the housing, a blade pivoted in the housing adapted to move inwardly through the slot and downwardly in the container adjacent the striker plate to cut one side and the base of the can so that the severed portions of the base are bent downwardly, means for forcing the blade inwardly and downwardly, spring means for moving the blade in the opposite direction, and means pivotally connected to the blade and to the closure for moving the latter away from the seat as the blade is moved inwardly and downwardly and for moving the closure toward the seat as the blade is moved in the opposite direction.

2. The combination in claim 1, wherein the means for forcing the blade inwardly and downwardly includes a block in the housing pivoted on the blade, an operating member pivoted in the housing and projecting outwardly therefrom, and a cam on the member cooperating with one surface of the block for moving the latter and the blade.
